UNITED STATES PATENT OFFICE.

ARTHUR UNDERWOOD, OF WASHINGTON, DISTRICT OF COLUMBIA.

FUEL-FEEDING SYSTEM FOR INTERNAL-COMBUSTION ENGINES.

Application filed March 2, 1922. Serial No. 540,596.

To all whom it may concern:

Be it known that I, ARTHUR UNDERWOOD, a citizen of the United States of America, and a resident of Washington, in the District of Columbia, have invented new and useful Improvements in Fuel-Feeding Systems for Internal-Combustion Engines, which invention is fully set forth in the following specification.

10 This invention relates to fuel feeding systems for engines and is especially adapted for use in connection with engines having a fuel supply at a lower level than the carburetor or other device through which 15 the fuel is supplied to the engine.

Various means have been employed to utilize the suction in the manifold of an engine for supplying the engine with liquid fuel from a fuel tank disposed at a lower 20 level than the carburetor, all of which embody a plurality of springs, valves and other moving parts, which parts add greatly to the cost of manufacture and are likely to become inoperative under the severe 25 conditions of operation to which they are subjected. It is an object of this invention to devise means for reducing the number of 30 these moving parts to a minimum in a fuel-feeding system which is actuated by the suction of an engine.

In devices of this nature it has been found necessary to provide the vacuum chamber or reservoir with separate inflow and outflow connections, or with valve 35 means, springs, etc., for controlling the outflow connections, admitting atmospheric pressure to said chamber or reservoir, etc.

Further objects of this invention are to 40 eliminate valves between the vacuum chamber and the inflow and the outflow connections; to provide an improved valve mechanism for controlling the suction connection to the engine manifold; and to provide a device which is simple in design, inexpensive to manufacture and highly efficient in 45 practical operation.

The inventive idea, set forth herein, is capable of being embodied in a variety of mechanical structures, two of which, for the 50 purpose of illustrating the inventive idea, are shown in the accompanying drawings, but it is to be expressly understood that the drawings are for the purpose of illustration only, and are not designed to define

the limits of this invention, reference being had to the appended claims for this purpose.

In the drawings:—

Fig. 1 is a side view, partly in section, of my improved fuel feeding device; 60

Fig. 2 is a top plan view;

Fig. 3 is an end view, partly in section; and

Fig. 4 is a side view, partly in section, of another embodiment of the invention. 65

In the form shown in Figs. 1, 2 and 3, a receptacle 10 of any suitable size, shape and proportions is mounted in any suitable way and connected to the source of fuel and the carburetor or other fuel-consuming 70 element of the engine. Preferably, receptacle 10 is located adjacent to and above the carburetor or other fuel-consuming element and connected, as by a pipe 11 extending through its bottom, with the carburetor. 75 The reservoir is illustrated as open to the atmosphere at its top, but any suitable cover (not shown), provided with an atmosphere inlet, may be secured to said reservoir to insure against loss of fuel contained therein. 80

Pivottally mounted in any suitable way in said receptacle is a chamber or vacuum tank 12, the axis of movement of the same being offset with respect to its center of gravity so that said tank tends to tilt around its axis as hereinafter explained. In the construction illustrated, the reservoir or receptacle 10 is provided with an L-shaped 85 supporting bracket 14 (see particularly Fig. 90 3) and the chamber or vacuum tank 12 is eccentrically pivoted on a bolt 15 which is threaded into the bracket and passes through a tubular sleeve 16 formed in any suitable way in the tank 12. 95

Communicating with the interior of the fuel reservoir or receptacle 10 is a connection leading to a source of suction which is preferably the intake manifold of the engine. In the construction illustrated, the 100 L-shaped bracket is utilized as the connection and is bored transversely of its horizontal inwardly directed end to provide the passage or port 17 which may be connected with the intake manifold by a pipe 18 105 communicating with said passage. Mounted within the bracket for reciprocation transversely of its passage 17 is a tubular

valve member 19 having the interior passage 20 and a transverse opening 21 communicating therewith in such position that it will communicate with passage 17 or 5 move opposite the solid portion of the wall of the passage 17 as said tubular valve member is reciprocated back and forth as hereinafter explained. One end of the valve member is provided with a vertical flange 10 22, while the opposite end of the valve member is provided with any suitable form of stop 23 to prevent its movement beyond a predetermined limit.

The chamber or vacuum tank 12 is constructed in any suitable way so that an opening therein will move into and out of register with the open end of the passage 20 in the valve member 17. In the construction illustrated, a box-like projection or deflecting member 24 is suitably secured, as by soldering, to the exterior wall of the tank 12, and has in its side facing the valve member 19, and preferably at one end of its lateral face, an opening 25 of substantially the same size as the opening through the passage 20. The interior of the box-like extension 24 communicates with the interior of the tank 12 by a small aperture 26 which is preferably disposed at the opposite end 20 of said box-like extension, so that any fuel which may be drawn through said aperture 26 into the box-like extension 24 will not be drawn directly through the aperture 25 into the connections to the intake manifold. 30 In place of the construction illustrated, however, any other suitable means may be employed for preventing any fuel which may be drawn into said box-like extension from passing directly into the suction connections.

The vacuum tank or chamber 12 is also supplied in any suitable way with inlet and outlet connections and, for simplicity of construction, the same connection is preferably used for both the admission of fuel thereto and the outflow of fuel therefrom. In the form shown a pipe or conduit 27 is introduced into the tank 12 through its under side and to prevent accumulation of 45 dirt from obstructing the inwardly directed end of said pipe, the latter may be closed at its inner end provided with lateral openings 28 for communication with the interior of the tank. Said pipe extends downwardly 50 within the receptacle 10 and is preferably reversely curved for a purpose to be hereinafter described. The receptacle 10 is also provided with an inflow connection or conduit 29 which may be supported from the 55 wall of the receptacle in any suitable way, being shown as mounted in the X-shaped bracket 14 heretofore described. The outer end of the connection 29 extends to a fuel tank positioned in any desired location but 60 ordinarily at a level below that of the re-

ceptacle 10. The inner ends of the inlet 27 and the inflow connection 29 are in alignment and adapted to be in engagement when the vacuum tank 12 has its aperture 25 in register with the end of the passage 20 in 70 the valve member.

The vacuum tank 12 is also provided with any suitable float for holding the vacuum tank with its aperture 25 disconnected from the passage through the valve member 19 75 when the level in the receptacle 10 rises above a predetermined limit. While the float may take a variety of forms, the construction shown in Fig. 1 comprises an air chamber 30 having a downwardly directed 80 open end extending to a level such that it is normally submerged in the fuel in the receptacle 10. Said air chamber may be formed integrally with the vacuum tank 12 or may be attached thereto in any suitable 85 way, being shown as formed with its closed end extending within the cylindrical surface of the vacuum tank.

The vacuum tank 12 is also provided with a suitable weight so that, when empty, its 90 aperture 25 is held in register with the end of the passage through the valve member 19. In the form illustrated, a weight 31 is suitably secured to the exterior surface of the tank 12 and is desirably provided with an upstanding arm 32 which is adapted to engage the outwardly projecting end 23 of the valve 19 and positively move its aperture 21 opposite the solid portion of the wall of the passage 17 in the event that said valve 100 member is not drawn into the last-named position by the suction tending to hold the surface of the flange 22 against the face of the box-like extension 24.

If desired, the inflow connection 29 may 105 be provided with any suitable form of check-valve 33 to prevent the column of oil within the piping leading from the fuel tank to receptacle 10 from flowing back into said tank at the rear end of the car when the connection between the inflow connection 29 and the inlet 27 is broken by the emptying of the tank 12.

It will be perceived that the lower end of the reversely curved inlet or conduit 27 115 is positioned below the open end of air chamber 30. Any air that may be drawn into the chamber with the fuel will escape upwardly into said chamber to replenish the air therein.

If for any reason the inlet 27 should abut against inflow connection 29 in such a manner that leakage occurs at this point, no objectionable result ensues since the butt connection is normally submerged in the fuel in 125 reservoir 10.

Since the reservoir 10 is usually above the level of the source of the fuel supply, the pivotally mounted chamber and reservoir will normally be empty. The position of 130

the chamber 12, in this condition, is such that inlet 27 registers with inflow connection 29, opening 25 in projecting element 24 registers with the passage 20 in valve member 19, and the transverse opening 21 is in communication with passage 17. When the engine is started, suction will be established through the above mentioned openings and passages to the intake manifold of the engine and a partial vacuum thus established in chamber 12 will result in the elevation of fuel through connection 29 and inlet 27 into chamber 12. When the fuel reaches a predetermined level in chamber 12, the chamber will be overbalanced and will move to the position shown in dotted lines in Fig. 1. During this movement, the suction will tend to maintain the butt connection between valve member 19 and the face of the box-like projection 24. This tendency will cause the valve to move with the chamber and opening 21 will be moved opposite the solid portion of the wall of the passage 17, thus closing the suction connection to the engine manifold. Should this movement of the valve not take place for any reason, arm 32 will engage the outwardly projecting end 23 of the valve 19 and positively move the valve and close the suction connection. The movement of the valve is more limited than that of the chamber and when the connection between the two is broken, further movement of the valve being prevented by stop means 23, atmospheric pressure is admitted to the chamber through openings 25, 26; the fuel contained therein escapes through inlet 27 into reservoir 10, and thence by gravity through outflow connection 11 to the float chamber of the carbureter. When emptied of its fuel in this manner, the chamber 12 is overbalanced in the opposite direction by weight 31, whereupon the chamber returns to the empty or filling position, reestablishing the butt connections between the flange 22 of valve 19 and the face of the box-like projection 24 and between inlet pipe 27 and inflow connection 29. This cycle of operations is continued until the liquid discharged by chamber 12 into the reservoir 10 reaches a predetermined level whereupon the float member 30 acts to move the chamber to or maintain it in the discharging position, shown in dotted lines in Fig. 1, regardless of the fuel contained therein. Additional fuel will not be introduced into the chamber or reservoir until the level of the liquid in the reservoir has been sufficiently lowered, by the discharge through the carbureter, to render the float incapable of holding the chamber out of filling position, whereupon the above-described cycle of operations will be resumed.

In Fig. 4 is shown an embodiment of the invention wherein a float member is pro-

vided for positively controlling the suction connection to the engine manifold when the fuel in the reservoir 10 has reached a predetermined level. While the float and its connections may take a variety of forms, the construction shown in Fig. 4 comprises an air chamber 34 having a downwardly directed open end which is normally submerged in the fuel in receptacle 10. Attached in any suitable way to the upper end of said chamber is a vertically disposed rod 35, pivotally attached, as at 36, to the lower arm of a suitable bell-crank lever 37, pivoted, as at 38, to an arm 39 which may be secured to the L-shaped bracket 14. The upper arm of lever 37 is suitably connected, as by a longitudinally extending opening or slot 40, to a pin 41 projecting transversely from a rod 42. If desired, the upper arm may be bifurcated to engage pin 41 on both sides of rod 42. This rod is adapted to reciprocate back and forth in the passage 43 of valve 44 as hereinafter explained. Suitable guide means may be provided to prevent lateral movement of the float or air chamber 34. In the construction illustrated, an arm 45 is provided with an opening, in one end thereof, adapted to engage the rod 35, while the opposite end of said arm is suitably secured to the L-shaped bracket 14, at a point such that the vertical oscillation of the air chamber 34 will not be limited by the arm.

When the fuel, discharged by the chamber or vacuum tank 46 into reservoir 10, as hereinbefore described, reaches a predetermined level, the float or air chamber 34 is carried upward by the fuel, thus actuating lever 37 and rod 42. Movement of rod 42 in passage 43 of valve 44, closes the transverse opening 47 in said valve, thereby closing the connection to the source of suction. Additional fuel will not be introduced into the chamber or reservoir until the level of the liquid in reservoir 10 has been sufficiently lowered, by the discharge through the carbureter, to render the float ineffective, whereupon the weight of the float or air chamber 34 actuates lever 37 to move rod 42 in the opposite direction until the transverse opening 47 is again uncovered, when suction to chamber 46 will be reestablished.

Any suitable stop means may be provided for limiting the movement of the vacuum chamber or tank. In the embodiment shown in Fig. 4, an arm 48 is secured to reservoir 10 in a position such that it coacts with a lateral face of box-like projection 24 to limit the tilting movement of the chamber or vacuum tank, whereby weight 31 is always maintained in a position, relative to the axis of movement passing through bolt 15, such that it tends to return said chamber to the filling position.

It will therefore be perceived that I have

provided a fuel feeding device for engines in which the number of moving parts has been reduced to a minimum. This feature is of prime importance from the standpoint of the user since it insures continuous operation and durability even under the most severe operating conditions. The simplicity of the device is of further value when considered from the manufacturing standpoint,

10 since it insures economical production.

While two embodiments of the inventive idea have been described herein with considerable particularity and detail, it is to be expressly understood that the invention is not limited thereto, as the same is capable of a variety of expressions, some of which will readily suggest themselves to those skilled in the art, while certain features thereof are capable of use without other features thereof. Reference is therefore to be had to the claims hereto appended for a definition of the limits of the invention.

What is claimed is:—

1. A fuel feeding system for engines including a reservoir having an inflow connection to a fuel tank disposed at a lower level and having an outflow connection to a carburetor, a valve in said inflow connection, a chamber pivotally mounted in said reservoir and having an inlet which registers with the inflow connection in one position of said chamber, said chamber being pivotally movable under the weight of fuel therein to empty through said inlet into said reservoir, a suction connection to the intake manifold of the engine, and valve mechanism controlled by the pivotal movement of said chamber for connecting and disconnecting said suction connection with said chamber.

2. A fuel feeding system for engines including a reservoir having an inflow connection to a fuel tank disposed at a lower level and having an outflow connection to a carburetor, a valve in said inflow connection, a chamber pivotally mounted in said reservoir and having an inlet which registers with the inflow connection in one position of said chamber, said chamber being pivotally movable under the weight of fuel therein to empty through said inlet into said reservoir, a suction connection to the intake manifold of the engine, valve mechanism controlled by the pivotal movement of said chamber for connecting and disconnecting said suction connection with said chamber, and float means for actuating said valve mechanism independently of the movement of said chamber under the weight of fuel therein.

3. A fuel feeding system for engines including a reservoir having an inflow connection to a fuel tank and having an outflow connection to a carburetor, a chamber movably mounted in said reservoir and having an inlet which registers with the inflow

connection in one position of said chamber, said chamber moving under the weight of fuel flowing thereinto to empty through said inlet, a suction connection to the intake manifold of the engine, and valve mechanism controlled by the movement of said chamber toward and away from said mechanism for connecting and disconnecting said suction connection with said chamber.

4. A fuel feeding system for engines including a reservoir having an inflow connection to a fuel tank and having an outflow connection to a carburetor, a valve in said inflow connection, a chamber movably mounted in said reservoir and having an inlet which registers with the inflow connection in one position of said chamber, said chamber moving under the weight of fuel flowing thereinto to empty through said inlet, a suction connection to the intake manifold of the engine, and valve mechanism controlled by the movement of said chamber for connecting and disconnecting said suction connection with said chamber, and means positioned exteriorly of said chamber whereby fuel flowing into said chamber cannot be drawn directly into said suction connection.

5. A fuel feeding system for engines including a reservoir having an inflow connection to a fuel tank and having an outflow connection to a carburetor, a chamber movably mounted in said reservoir and having an inlet which registers with the inflow connection in one position of said chamber, said chamber moving under the weight of fuel flowing thereinto to empty through said inlet, a suction connection to the intake manifold of the engine, valve mechanism controlled by the movement of said chamber for connecting and disconnecting said suction connection with said chamber, and float means for actuating said valve mechanism independently of the movement of said chamber under the weight of fuel therein.

6. A fuel feeding system for engines including the combination of a reservoir having an inflow connection from a source of fuel, and an outflow connection adapted to be connected with a carburetor, a chamber pivotally mounted in said reservoir and having an inlet adapted to register below the normal level of the fuel in said reservoir with said inflow connection in the filling position of said chamber, said chamber moving under the weight of fuel flowing thereinto to empty through said inlet.

7. A fuel feeding system for engines including the combination of a reservoir having an inflow connection from a source of fuel, and an outflow connection adapted to be connected with a carburetor, a chamber movably mounted in said reservoir and having an inlet pipe adapted to register with

- 5 said inflow connection in the filling position of said chamber, said chamber moving under the weight of fuel flowing thereinto to move said inlet pipe upwardly and away from said inflow connection and to empty through the same, and means including a connection with the intake manifold, whereby suction is admitted to the interior of said chamber to fill the same.
- 10 8. A fuel feeding system for engines including the combination of a reservoir having an inflow connection to a source of fuel, and an outflow connection adapted to be connected with a carburetor, a chamber movably mounted in said reservoir and having an inlet adapted to register below the normal level of the liquid in said reservoir with said inflow connection in the filling position of said chamber, said chamber moving under the weight of fuel flowing thereto into to empty through said inlet, means including a connection with the intake manifold, whereby suction is admitted to the interior of said chamber to fill the same, and means operated by the movement of said chamber for connecting and disconnecting said suction connection with said chamber.
- 15 9. A fuel feeding system for engines including the combination of a reservoir having an inflow connection adapted to be connected with a source of fuel, and an outflow connection adapted to be connected with a carburetor, a chamber movably mounted in said reservoir and having an inlet adapted to register with said inflow connection in the filling position of said chamber, a suction connection to the intake manifold of the engine, and means rendered effective by suction for closing said suction connection.
- 20 10. A fuel feeding system for engines including the combination of a reservoir having an inflow connection adapted to be connected with a source of fuel, and an outflow connection adapted to be connected with a carburetor, a chamber movably mounted in said reservoir and having an inlet adapted to register with said inflow connection in the filling position of said chamber, a suction connection, and rectilinear movable means rendered effective by an element carried by said chamber for closing said suction connection.
- 25 11. A fuel feeding system for engines including the combination of a reservoir having an inflow connection adapted to be connected with a source of fuel, and an outflow connection adapted to be connected with a carburetor, a chamber movably mounted in said reservoir and having an inlet adapted to register with said inflow connection in the filling position of said chamber, a suction connection, and a valve, flanged at the opposite ends thereof, rendered effective by suction for closing said suction connection,
- 30 and an element carried by said chamber for positively actuating said means when the same is not rendered effective by suction.
- 35 12. In a device of the character described, the combination of a reservoir for liquid fuel having an atmosphere inlet, an outflow connection and an inflow connection from a lower source of liquid fuel supply, a chamber pivotally supported in said reservoir having connection with a source of suction exterior to said reservoir and an inlet adapted to register with the inflow connection of the reservoir whenever the chamber is in filling position, said chamber being so pivoted that when empty of liquid fuel it is overbalanced in the direction for forming below the normal level of the fuel in said reservoir a connection between said inflow connection and inlet, whereby liquid fuel is sucked thereinto from said lower source of liquid fuel supply.
- 40 13. A liquid fuel vacuum-feed device comprising a reservoir, an inflow connection from a lower source of liquid fuel supply, a chamber pivotally supported by said reservoir, a conduit carried by said chamber and adapted to form a butt connection with the inflow connection below the normal level of the fuel in said reservoir, a suction connection carried by said reservoir, an opening in said chamber adapted to register with said suction connection, and means for closing said suction connection.
- 45 14. In an apparatus for utilizing the suction of an engine for supplying a carburetor with liquid fuel, the combination of a reservoir, an outflow connection carried thereby, a supporting member mounted therein, an inflow connection from a lower source of liquid fuel supply, a chamber eccentrically pivoted to the supporting member, a conduit extending downwardly from said chamber and adapted to form a connection with said inflow connection, a suction connection carried by said supporting member, a connection between said chamber and said suction connection, and means for closing said suction connection actuated by movement of said chamber away from said suction connection under the weight of the liquid directed thereinto.
- 50 15. In a device of the class described, the combination of a reservoir for liquid, an atmosphere inlet, an inflow connection, and an outflow connection, a supporting element, a chamber pivotally mounted on said element and adapted when empty to be overbalanced in one direction, a connection between the chamber and inflow connection when the chamber is in the empty position, a suction connection carried by said supporting element, and means drawn into closed position by pivotal movement of said chamber for closing the suction connection.
- 55 16. An apparatus for utilizing the suction

of an engine for elevating liquid fuel from a tank to a point above a carburetor including a reservoir, a chamber tiltably mounted therein, an inflow connection within said reservoir having a butt connection with said chamber, a suction connection, and means drawn into closed position by the movement of the chamber under the weight of the liquid directed thereinto for closing said suction connection.

17. In a device of the class described, the combination of a reservoir for liquid fuel, an atmosphere inlet, an outflow connection, an inflow connection from a lower source of liquid fuel supply, a chamber tiltably mounted in said receptacle, suction means, a connection between said means and chamber, a deflecting element carried by said chamber exteriorly thereof, and a connection between the chamber and inflow connection whereby liquid is sucked thereinto from said lower source of liquid supply.

18. In a device of the class described, the combination of a reservoir, an atmosphere inlet, an outflow conduit and an inflow connection from a lower source of liquid fuel supply, a supporting element mounted in the receptacle, a suction connection carried by said element, rectilinear movable means for closing the suction connection, a suction chamber adapted to register with said inflow connection, and means operated by the liquid in said reservoir for actuating the means for closing the suction connection.

19. In a device of the class described, the combination of a reservoir, a liquid supply inlet, a chamber movably mounted in the reservoir and adapted when liquid-filled to a predetermined degree to be overbalanced in one direction, a conduit carried by the chamber having a butt connection with said supply inlet, a suction port, and means actuated by movement of the chamber away from said port when liquid-filled for closing said port.

20. In a device of the class described, a reservoir, a chamber tiltably mounted therein, an inflow conduit having a butt connection with said chamber, a suction connection for said chamber, and rectilinear movable means for closing said connection.

21. In a device of the class described, a reservoir, a chamber tiltably mounted therein, a liquid inlet connection from a lower source of liquid supply, a butt connection between said chamber and connection below the normal level of the fuel in said reservoir, a suction connection for said chamber, means for closing said suction connection, and a float for actuating said last-named means.

22. A fuel feeding system for engines including the combination of a reservoir having an inflow connection from a source of fuel, and an outflow connection adapted to

be connected with a carburetor, a chamber movable mounted in said reservoir and having an inlet adapted to register with said inflow connection in the filling position of said chamber, a suction connection, a tubular valve adapted to control the suction connection, and means comprising an open-ended air chamber for controlling the actuation of said valve when the fuel in said reservoir has reached a predetermined level. 75

23. A fuel feeding system for engines including the combination of a reservoir having an inflow connection from a source of fuel and an outflow connection adapted to be connected with a carburetor, a chamber movably mounted in said reservoir and having an inlet adapted to register with said inflow connection in the filling position of said chamber, a suction connection to the manifold of an engine, and a box-like projection 80 on said chamber having a butt connection with said suction connection when the chamber is in the filling position.

24. A fuel feeding system for engines including the combination of a reservoir having an inflow connection from a source of fuel and an outflow connection adapted to be connected with a carburetor, a chamber movably mounted in said reservoir and having an inlet adapted to register with said inflow connection in the filling position of said chamber, a suction connection to the manifold of an engine, and a tubular valve for controlling said suction connection. 85

25. A fuel feeding system for engines including the combination of a reservoir having an inflow connection from a source of fuel and an outflow connection adapted to be connected with a carburetor, a chamber movably mounted in said reservoir and having an inlet adapted to register with said inflow connection in the filling position of said chamber, a suction connection to the manifold of an engine, a tubular valve for controlling said suction connection, and an 100 arm carried by the chamber for actuating said valve. 105

26. A fuel feeding system for engines including the combination of a reservoir having an outflow connection adapted to be connected with a carburetor, a chamber movably mounted in said reservoir, an open-ended inflow connection from a source of fuel, and an open-ended inlet carried by said chamber having a butt connection with said inflow connection when the chamber is in the filling position, said butt connection being normally below the level of the fuel in said reservoir. 115

27. A fuel feeding system for engines including the combination of a reservoir having an inflow connection from a source of fuel, and an outflow connection to a carburetor, a chamber movably mounted in said reservoir and having inlet and outlet con- 120 130

nections, said inlet connection communicating below the normal level of the fuel in said reservoir with the inflow connection when the chamber is in filling position, said 5 inlet and outlet connections being opened and closed by the movement of the chamber to bring the chamber into and out of filling position.

28. A fuel feeding system for engines including the combination of a reservoir having an inflow connection from a source of fuel, and an outflow connection to a carburetor, a chamber movably mounted in said reservoir, a suction connection to the manifold of an engine, and a downwardly projecting tube interposed between said inflow connection and chamber whereby movement of the chamber into and out of filling position permits suction to draw fuel into the 20 chamber and allows fuel to flow out of said chamber.

29. A device of the class described comprising a reservoir for liquid fuel having an outflow connection, means connecting said reservoir with a lower source of liquid fuel supply and permitting the flow of liquid fuel therein in only one direction, a chamber movably mounted in said reservoir, an inlet pipe for said chamber extending 30 downwardly therefrom into operative relation with said means when the chamber occupies a predetermined position, and a suction connection to the intake manifold of an engine for said chamber, said chamber being adapted to move under the weight 35 of liquid fuel flowing thereto to empty through said inlet pipe into said reservoir.

30. In a device of the class described, a reservoir having an outflow connection 40 to a carburetor, a chamber tiltably mounted therein, an inflow connection for said reservoir connecting the latter with a lower source of fuel supply and having a butt connection with said chamber below the normal level of the fuel in said reservoir 45 when said chamber is tilted to filling position, a suction connection for said chamber, and rectilinearly movable means for closing said suction connection.

31. In a device of the class described, a reservoir having an inflow connection from a source of fuel and an outflow connection to a carburetor, a chamber movably mounted in said reservoir having an opening 50 therein adjacent the upper portion thereof and having an inlet adapted to register

with said inflow connection when said chamber is in filling position, a suction connection for said chamber, and means for closing said suction connection, said opening being adapted to form a passage through which suction is introduced into said chamber when the same is in filling position and also to form a passage for admitting atmospheric pressure into said chamber when 65 the latter is in emptying position.

32. A device of the class described comprising a reservoir having an inflow connection from a lower source of fuel supply, an outflow connection to a carburetor 70 and an atmosphere inlet, a chamber movably mounted in said reservoir having an atmosphere inlet and an inlet pipe adapted to register with said inflow connection below the normal level of fuel in said reservoir when the chamber is in filling position, a suction connection for said chamber, and means for closing said suction connection, the atmosphere inlet in said chamber being adapted to register with said suction 75 connection when the chamber is in filling position.

33. A device of the class described comprising a reservoir having an outflow connection to a carburetor, an inflow connection for connecting said reservoir to a lower source of fuel supply, a chamber movably mounted in said reservoir and having an inlet communicating with said inflow connection below the normal level of fuel in 80 said reservoir when said chamber is in filling position, and a suction connection communicating with said chamber when the latter is in filling position.

34. A device of the class described comprising a reservoir having an outflow connection to a carburetor, an inflow connection for connecting said reservoir to a lower source of fuel supply, a chamber movably mounted in said reservoir and having an 85 inlet communicating with said inflow connection below the normal level of fuel in said reservoir when said chamber is in filling position, said chamber being adapted to empty through said inlet below the said 90 level of fuel when the chamber moves to emptying position, and a suction connection communicating with said chamber when the latter is in filling position.

In testimony whereof I have signed this 110 specification.

ARTHUR UNDERWOOD.
